LAST

Harold Goodman, Peabody, and Earl J. McGown,
Lynn, Mass.

Application March 18, 1940, Serial No. 324,464

1 Claim. (Cl. 12—136)

This invention relates to hinged lasts and has for its object the production of a single spring element serving as a connector between the two parts of the last, which element will hold said parts rigidly together when either in extended or shortened position while permitting slight relative movement of said parts toward and from each other at intermediate points.

This object is attained by the mechanism illustrated in the accompanying drawing.

For the purpose of illustrating the invention, one preferred form thereof is illustrated in the drawing, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claim.

Of the drawing

Figure 1 represents a longitudinal vertical section of a two part last, the two parts of which are connected by a single spring element embodying the principles of the present invention, the last being shown extended.

Figure 2 represents a similar section showing the last shortened.

Figure 3 represents a horizontal section of the portion of the last on line 3, 3 on Fig. 1.

Figure 4 represents a section of the fore part of the last on line 4, 4 on Fig. 1.

Figure 5 represents a section of the heel part on line 5, 5 on Fig. 1, and

Figure 6 represents an elevation of the spring element removed from the last.

Similar characters indicate like parts throughout the several figures of the drawing.

In the drawing, 10 is the fore part of a divided last having formed in its rear face a curved depression 11 extending transversely thereof.

The heel part 12 has formed on its front face a semi-cylindrical projection 13 adapted to be positioned in the depression 11 and contact with the wall thereof.

The depression 11 is semi-cylindrical and has a radius slightly exceeding that of the semi-cylindrical projection 13.

Owing to the differences in the radii of the projection 13 and depression 11, the outer surface of the projection 13 will not contact with the surface of the depression 11 at the top and bottom thereof.

The fore part 10 is provided with a vertical slot 55

or recess 14 in its rear end which is alined with a similar slot or recess 15 formed in the front end of the heel part 12.

The side walls of the slots or recesses 14 and 15 are perfectly flat and parallel to each other.

Extending transversely of the slot or recess 14 is a cylindrical pin 16 embedded in the fore part 10 and in the heel part 12 is another cylindrical pin 17 extending transversely of the slot or recess 15.

Mounted on these pins 16 and 17 and disposed within the slots or recesses 14 and 15 is a single spring element 18, as shown in Fig. 6 of the drawing.

15 This spring element 18 is bent upwardly in the center thereof as indicated at 19 in Fig. 6 of the drawing, and the opposite ends 20 thereof are bent upwardly parallel to the surfaces 21 of said spring element.

20 Between the surfaces 21 and the upwardly bent ends 20, the pins 16 and 17 are adapted to be disposed.

This spring element 18 is of the same thickness as the width of the recesses 14 and 15, 25 and is provided on its opposite faces with flat surfaces 22 which bear against the side walls of the recesses 14 and 15 when the last is being shortened or lengthened.

These flat surfaces 22 contacting with the walls 30 of the recesses 14 and 15 retain the two parts 10 and 12 of the last in proper alinement at all times.

35 The spring element 18 is highly tempered and notwithstanding the size of said spring element, it is sufficiently resilient to permit the movement of one last part 10 relative to the other last part 12.

When the last is straightened as shown in Fig. 1 of the drawing a portion of the periphery of 40 the semi-cylindrical projection 13 will be held in rigid contact with the central portion of the depressions 11 and the center line between the pins 16 and 17 will be considerably below the axis 23 of the projection 13.

45 When shortening the last by moving the fore part 10 about the axis 23 and relatively to the heel part 12, said axis 23 must move toward the bottom of the last and pass across the center line between the centers of the pins 16 and 17.

50 Owing to this center line between the pins 16 and 17 being well below the axis 23 of the projection 13 when the last is shortened as shown in Fig. 2, the fore part 12 can be moved about said axis 23 in order to lengthen the last only by applying great pressure thereto.

As this pressure is applied to the fore part to move it about said axis 23, the single spring element 18 will straighten sufficiently to permit this movement and then return to its normal curved condition.

Even when the last is shortened and in the position indicated in Fig. 2 of the drawing, it is only by applying considerable pressure to the fore part 10 that said fore part may be moved about the axis 23 to lengthen the last into its extended position as indicated in Fig. 1.

As a consequence, the two parts 10 and 12 of the last are connected by a single element in such a manner that the last is very rigid when in either shortened or extended position.

It will be noted that upon breaking the last when in its extended position the last will immediately commence to shorten.

The projection 13 of the heel part 12 resting in the depression 11 of the fore part forms a knuckle joint.

It is quite obvious that when a shoe is on a last and is being operated upon in the manufacture thereof, it is very essential that the last should have a great degree of rigidity and this result is produced very effectually by the method herein shown and described.

It is believed to be novel to connect the two parts 10 and 12 of the last by means of a single spring element dispensing with other instrumentalities which have been found necessary in other constructions of connecting means between the two parts of the last.

Owing to the increased size of the spring element 18 over similar spring elements heretofore in use, it has been found an advantage to have

the opposite ends 20 of the spring element 18 parallel with the surfaces 21, thereby making these ends much stronger.

When these ends 20 are curved around the pins 16 and 17, the spring element is weakened at this point and there has been liability to breakage, necessitating the replacing of the broken spring elements with new spring elements.

The spring element 18 is hardened at 1500° F., then quenched in oil, and then tempered at 850° F. for two hours.

By means of the construction herein shown and described a very strong two part last is provided which is capable of meeting hard usage and at the same time owing to the dispensing of many other instrumentalities heretofore in use the last is made at a minimum expense.

It is believed that the operation and many advantages of the invention will be understood without further description.

Having thus described our invention, we claim:

A last having two parts arranged for movement relatively to each other about a knuckle joint and each part provided with a relatively wide vertical recess with flat parallel side walls; a pin extending transversely of each recess and spaced from the axis of said knuckle joint; and a sole connector within and contacting with the side walls of said recesses between said pins, said connector having slight vertical movement in said recesses during the relative movement of the last parts, and said connector being provided with an arch shaped resilient central portion and having opposite curved ends partially surrounding said pins.

HAROLD GOODMAN,
EARL J. McGOWAN.
